US00D857192S

(12) **United States Design Patent** (10) **Patent No.:** **US D857,192 S**
Burkett et al. (45) **Date of Patent:** **** Aug. 20, 2019**

(54) **AUTOINJECTOR DEVICE**

(71) Applicant: **Merck Sharp & Dohme Corp.**,
Rahway, NJ (US)

(72) Inventors: **Greg Burkett**, San Francisco, CA (US);
Shu Kuen Chang, Evanston, IL (US);
Angie Kim, San Francisco, CA (US);
Jin Ko, Evanston, IL (US); **Scott Mackie**, New Haven, CT (US); **Philip G. Green**, Weehawken, NJ (US);

(57) **CLAIM**

The ornamental design for an autoinjector device, as shown and described.

DESCRIPTION

FIG. 1 is a front perspective view of an autoinjector pen in accordance with the present invention with the cap attached; FIG. 2 is a front elevational view thereof, the rear being a mirror image;

FIG. 3 is a top plan view thereof;

FIG. 4 is a bottom plan view thereof;

FIG. 5 is a left side elevational view thereof, the right side being a mirror image;

FIG. 6 is a front perspective view thereof with the cap removed;

(Continued)

FIG. 7 is a front elevational view thereof, the rear being a mirror image;

FIG. 8 is a left side view thereof, the right side being a mirror image;

FIG. 9 is another front elevational view of the autoinjector pen without the cap; and,

FIG. 10 is a bottom plan view thereof.

Broken lines, within the claimed design, are for illustrative purposes only and form no part of the claimed design.

The stippling in the drawings denotes texture.

The diagonal lines in the drawings indicate transparency.
